UNITED STATES PATENT OFFICE.

JOHN T. WILMORE, OF SEATTLE, WASHINGTON.

BLANK-FEEDING DEVICE.

1,300,084.

Specification of Letters Patent.

Patented Apr. 8, 1919.

Application filed April 5, 1915. Serial No. 19,369.

To all whom it may concern:

Be it known that I, JOHN T. WILMORE, a citizen of the United States, residing at Seattle, in the county of King and State of Washington, have invented certain new and useful Improvements in Blank-Feeding Devices, of which the following is a specification.

My invention relates to machines which are employed in making tin cans and consists of a device for feeding single can-body blanks to the mechanisms which act thereon to form the can body. My invention comprises the novel parts and combinations of parts which will be hereinafter described and particularly pointed out in the claims.

The object of my invention is to provide a feeding device for blanks of this kind which shall be certain in its action, both as to reliability of feeding and of feeding but one blank at a time, and one which is capable of a higher rate of operation than the devices which are in common use. Other objects will be hereinafter set forth.

25 In the accompanying drawings I have shown my device embodied in the constructions which are now preferred by me.

Figure 1 is a plan view of my device, showing the pile from which the blanks are to be fed and two blanks which have been withdrawn from the pile.

Fig. 2 is a side elevation of the same parts.

Fig. 3 is a cross section taken on the line 3, 3, of Fig. 1.

35 Fig. 4 is an end elevation taken from the delivery end of the device.

Fig. 5 is a side elevation of the working parts of the device showing these parts in a different position from that shown in 40 Fig. 2.

Fig. 6 is a like view showing these parts in the position occupied at a little later point in the stroke of the reciprocating blank-delivering parts.

45 Fig. 7 is a cross sectional elevation taken from the delivery end of the device, the parts being in the position assumed at a somewhat later stage of the stroke.

It is believed to be generally true, that the 50 speed of operation of a can making machine, is determined by the rate at which the blanks may be removed from a pile and delivered to the forming mechanisms. Any change

which will increase the speed of feeding the blanks, will correspondingly increase the 55 output of the machine. It has therefore been my object, first, to produce a device which may be operated at a higher rate of speed. At the same time, it has also been my object to have the same device thoroughly dependable in its operation, both as to certainty of removal of a blank each time it is operated, and also as to certainty that it will remove only one blank at a time.

The mechanisms by which I secure these 65 results, as herein shown are as follows:

The blank sheets are shown at 1, piled upon each other and held in position by angle bars 10, placed at two corners of the pile and a bar 11, placed centrally of the other 70 side. The bar 11 is upon the side from which the blanks are withdrawn and consequently extends downward only a short distance beneath the bottom of the pile.

The pile of blanks are supported centrally 75 by bars 2, which have a reciprocative movement beneath the pile, whereby there is a short time during each reciprocation, in which these bars are withdrawn, during which time the central support for the pile 80 is supplied by other members, as the separating finger 4 and the supplemental bar 26.

The separating finger 4, bar 26 and bars 2, are all connected to reciprocate alike, as by securing them to the slides 24. Small plates 85 23 secure the bars 2, which serve to remove the blanks after they have been separated from the pile, to the slides 24, while an arm, as 25, secures the bar 26 to the same slide.

The separating finger 4 may be secured to 90 move with these parts, as by an arm 40, (see Fig. 4) which connects it with the bar 26. The peculiar shape of the arm 40, is necessitated by having to pass the removed blanks back under the separating finger 4. 95

The two bars 2 lie parallel with the separating finger 4, but are separated therefrom lengthwise thereof, as is seen in Figs. 1, 2, 5 and 6. The ends of the bars 2 which are next to the finger 4, are cut to form inclines 20, 100 which surfaces face upwardly, and second inclines 21, which face downwardly, and a bottom finger 22 which has a level upper surface and projects well beyond the point formed by the meeting of said surfaces 20 105 and 21.

The separating finger 4 projects or overhangs from its supporting arm, a distance substantially as great as the width of a blank. Its pointed end 41 faces toward the 5 notched end of the bars 2, slightly overlapping the tip or arm 22. The arm 26 projects or overhangs similarly and has its end inclined or beveled to form a wedge surface 27, which faces upwardly and lies lower 10 than the separating finger 4. The three parts, bars 2, separating finger 4 and bar 26, reciprocate together, occupying at all times the same position relative to each other.

Under one end of the pile of blanks 1, 15 a supporting ledge 16 is provided. Aside from this fixed support, the pile of blanks is supported from the bars 2, 4 and 26, which are supported from a reciprocating carriage. Under the other end of the pile 20 of blanks is provided some device which will draw down this unsupported end of the lowermost blank. Such means might be a magnet, either a permanent magnet or an electromagnet, but I prefer to use a vacuum cup or sucker.

Such a sucker is shown at 31, this being carried by an arm 30 which is pivoted at 39 upon a fixed support. The shape of this arm should be such as to avoid interference 30 with the reciprocating parts of the carriage. The suction of this cup should be preferably intermittent, whereby the releasing of the sucker occurs through restoration of atmospheric pressure therein. This may be 35 most conveniently caused by employing a suction cylinder and piston which produces a draft on the sucker, this being automatically released when the separating finger has entered between the outer plate and the 40 pile.

An air cylinder 33 may be employed, having connection, as by a rubber tube 32, with the sucker. The piston 36 has its rod 35 connected with a moving part of the device 45 to be operated in unison with the fingers 2, 4 and 26. I have shown the cylinder as placed with its axis parallel the direction of reciprocation of the slide which also carries these fingers and the piston rod connected therewith, as by an arm 37.

The plate 5 has a slot therein, consisting of the straight sections 50 and 52, which parallel the direction of its reciprocations, and an inclined section 51 connecting these. 55 The sucker is connected, as by a link 56, with a bar 54, which is pivoted at 55 and carries a roller 53 which enters the slot in the plate 5, so that the sucker is thus raised and lowered as the plate 5 reciprocates.

60 With the carriage and the bars 2, 4 and 26, retracted from beneath the pile of blanks, the piston 36 is at the bottom of the cylinder 33 and the sucker is up with its head in contact with the lowermost blank 1. The 65 return movement of the carriage does not

draw down the sucker until the piston has been drawn back a short distance, enough to produce a sufficient vacuum to carry with it the unsupported end of this lowermost blank.

The point 41 of the separating finger, 4 then enters between this down-drawn end of the blank and the blank next above it, as is shown in Fig. 3, thereby securing a positive separation of this blank from the others. 75 As the movement progresses, the piston uncovers a slot 34 in the side of the cylinder, admitting air and releasing the grip of the sucker. At about the time the vacuum is broken, which follows closely after the entrance of the finger 4 between the blanks, the incline 27 on the end of arm 26, engages the edge of the separated plate, between the end of the plate and the separating finger 4, to force this end of the plate upward. Following shortly after this, the bars 2 reach a position where the notched ends thereof pass from beneath the farther edge of the pile of blanks. The lowermost plate, being tensed downwardly by the action of finger 4, flies down so as to bring its central part against the finger 22, or into the position shown in Fig. 7, in which position it will clear the bar 11 when drawn out.

With the return movement of the carriage, the rear edge of the blank is engaged by the inclined surface 21, being thereby held down and forced forward and onto the reciprocating bars 24, further advancing the blanks; or they may be engaged and fed to 100 the can body forming machine in any suitable manner, as by engagement with hooks 28 carried upon bars 24.

While I have shown and described my invention as acting by first pulling down an 105 unsupported end of the blanks, the same mechanisms may be employed, acting in an analogous manner, by supporting the blanks by their ends and applying the sucker to pull down the center of the pile of blanks, for the 110 entrance of the separating finger.

I have found that, by using a sucker, or some equivalent device, by which the lowermost plate may be drawn down, and combining with this a positive separating member, I can attain a much higher rate of speed 115 in feeding, than I have been able to attain by any of the common types of mechanisms. The sucker is relied upon to separate the blanks only enough to permit entrance of the point of the separating finger. After this, the mechanism by which the blank is handled is wholly of a positive and rapidly acting character.

By the embodiment of my invention 125 shown herein, one end of the pile of blanks is unsupported for some distance, and the sucker is applied to the blanks close to this unsupported end, wherefrom it follows that the bottom blank may be drawn down by the 130

expenditure of much less force, than if the blanks were supported near each end and the central section thereof were engaged by the sucker to draw it down. The sucker 5 may, however, be made of a size to handle the blank at either point.

Where central engagement of the sucker with the blanks is used, there is a certain amount of frictional resistance, caused by 10 the endwise movement produced between the blank and its support, when the center of the blank is drawn down. If the pile of blanks is considerable, this resistance may be considerable. Nothing of this sort occurs when their end is unsupported and the engagement is with this end. With a sufficiently powerful sucker this may be ignored.

There is a further reason, probably of 15 greater force, why pulling down the end is best. In the latter plan there is unrestricted access of air between the lowermost blank and that next above it, while when pulling down at the center, the inflow of air between the blanks is restricted. This may be 20 enough to produce a considerable resistance.

When reliance is had upon simultaneous 25 pulling down of both ends, to enable the removing member to engage therewith, it may, and does often happen, that one end 30 does not come down, while the other does. The result is the blank is engaged by one end to pull it out while the other is not. The result is that the blank is twisted about in the machine and possibly a wreck, or at 35 least, a serious derangement of the machine occurs. Such result not only stops this particular machine, but all other machines following it in the line of operations.

In handling the blanks as it is done with 40 this machine, by first pulling down a free and unsupported end by a single device, while the removing mechanism engages the blank at each side its center, it is certain that, either both the removing devices engage the 45 blank to properly remove it, or neither engages it. There can thus be no wreck caused by a failure to properly feed.

It is desired to call attention to the fact 50 that the preliminary separation of the blank from the pile, caused by the successive actions of the sucker and the fingers 4 and 26, occurs during a movement of the carriage in one direction, while the removal of the blank from beneath the pile occurs during the 55 movement of the carriage in the other direction. The various steps of the blank removing and feeding operation are thus distributed throughout the complete cycle of reciprocations, thereby increasing the time 60 available for certain steps while decreasing the time of a complete cycle of steps.

It is also desired to call attention to the 65 fact that the sucker is freed from the blank by admission of air thereto before the lateral removal of the blank is started, there be-

ing no tearing loose from the sucker by pulling sidewise while the suction is on. The wear upon the sucker face is therefore largely eliminated. The release of the sucker is further hastened by action of the incline 70 27 of finger 26 in throwing up this end of the blank.

Having now described my invention, what I claim and desire to secure by Letters Patent of the United States is:

1. A means for feeding blanks comprising a movable support for the pile located some distance inward from one end, the blanks at this end being unsupported outwardly of said support, means for separating this unsupported end of the first blank from the remainder, a separating finger movable in conformity with the movable support for the blanks to enter between the separated end of the first blank and the remainder, and means for engaging and removing the separated blank.

2. A mechanism for feeding blanks comprising means for supporting a pile of the blanks with one end overhanging the supports a considerable distance, the supporting member nearest this end being movable transversely of the blanks to be withdrawn therefrom, and a separating finger movable in unison with said supporting member and inserted between the outer and the remaining blanks as the said supporting member is withdrawn.

3. A mechanism for feeding blanks comprising means for supporting a pile of the blanks with one end overhanging the supports a considerable distance, the supporting member nearest this end being movable transversely of the blanks to be withdrawn therefrom, means for deflecting the lowermost blank from the remainder and a separating finger connected to move with said supporting member and entering between said deflected blank and the remainder as said supporting member is withdrawn.

4. A mechanism for feeding blanks comprising means for supporting a pile of the blanks with one end overhanging the supports a considerable distance, the supporting member nearest this end being movable transversely of the blanks to be withdrawn therefrom, and carrying blank-engaging and removing means, and a separating finger movable in unison with said supporting member and inserted between the outer and the remaining blanks as the said supporting member is withdrawn.

5. A mechanism for feeding blanks comprising means for supporting the blanks to leave one end thereof overhanging, said blank-supporting means comprising a member mounted for reciprocation transversely of the pile of blanks, a pair of blank supporting bars carried by said reciprocating member and located at each side of the cen-

- ter thereof, said bars having catches engaging the blanks when removed from the face of the pile, means for engaging the overhanging end of the outermost blank to deflect it away from the others, and a separating finger entering between said deflected blank and the others to throw the body thereof away from the others when said central movable supports are withdrawn.
- 10 6. A blank feeding device comprising a pile-retaining means engaging the edges of the blanks to retain them in place, a carriage mounted to reciprocate transversely of the pile, pile-supporting fingers reciprocating with said carriage and engaging the side face of the outermost of the blanks at each side the center thereof, one end of said supporting fingers being adapted for engagement, during their reciprocation, with the edge of the blanks when the latter are separated from the pile, means for deflecting an overhanging end of the outermost blank and a separating finger carried by the carriage and entering between the deflected end 25 of the blank and the remaining blanks of the pile.
7. A separating means for blanks comprising a finger adapted for insertion between the outermost blank and the others, and a complementary finger inclined upwardly and back from its end and adapted to engage the outer face of the same blank between the separating finger and the adjacent end of the blank.
- 30 8. A means for separating one from a pile of blanks comprising two fingers and means for reciprocating them transversely of the blanks, that one of the fingers which is nearest the end of the blanks having a surface which is inclined upwardly and back from the end of the finger, and which engages the outer surface of the blank which is being removed, the other finger engaging the inner surface of the blank which is being removed.
9. A means for separating one from a pile of blanks comprising two fingers and means for reciprocating them transversely of the blanks, and means for deflecting an end of the outermost blank of the pile, that one of the fingers which is nearest the end of the blanks having an inclined surface which engages the outer surface of the blank which is being removed and the other finger engaging the inner surface of the blank which is being removed.
- 40 10. A means for separating one from a pile of blanks comprising two substantially parallel fingers connected to move together and extending transversely of the pile of blanks near one end thereof, means for reciprocating these fingers to pass them under and withdraw them from beneath the pile, means for positioning the end of the outermost blank of the pile to cause the

point of the innermost of said fingers to pass between said blank and the others of the pile and the outermost of said fingers to engage the outer surface of the blank being removed, the blank-engaging side of 70 said latter finger being inclined to its direction of reciprocation to force the end of the blank back toward the pile.

11. A mechanism for separating one from a pile of blanks, comprising three fingers 75 connected to move together, one of said fingers acting to normally sustain the pile of blanks near the center of their length and having a catch adapted by its end to engage the edge of a blank to remove it from the pile when the blank has been separated from the pile, the other two fingers being located near the end of the pile of blanks, the innermost of these two fingers being in position to enter its point between 80 the outermost blank and the others when said outermost blank is deflected away from the pile, and the outermost finger having an inclined surface engaging the outer surface of said deflected blank to force it toward the 85 pile.

12. A mechanism for removing one from a pile of blanks comprising three fingers separated laterally from each other and connected to move together, in the direction of 90 their length, one of said fingers being placed to reciprocate beneath the central portion of and to support the pile, and to be withdrawn from beneath the pile, the other two fingers being offset lengthwise 100 their axis from said first named finger and being located toward one end of the pile, the innermost of said two fingers being adapted for entering between the outermost blank and the others and the outermost of said two fingers engaging the outer surface of said outermost blank and being inclined to force the end of the blank back toward the pile.

13. A blank feeding device comprising 110 means engaging the edges of a pile of blanks to retain them together, reciprocating blank-supporting members adapted to engage the central portions of the face of the lowermost blank to support the pile and to be withdrawn therefrom, an end of the blanks projecting beyond their supports to permit deflecting thereof, a deflecting member acting by attraction upon the face of the outermost blank to deflect its unsupported end, a 115 blank separating finger and a blank bending finger engaging respectively with the inner and with the outer surfaces of the outer blank, and means for reciprocating said fingers and the blank supporting members in conformity.

14. A blank feeding device comprising blank supports adapted to be withdrawn from beneath the pile of blanks, and also adapted to permit deflection of one end of 130

the blanks, a suction device adapted to engage the same end of the blanks to deflect the outermost, and positive acting means entering between said blank when deflected 5 and the other blanks.

15. A blank feeding device comprising combined supporting and withdrawing members engaging the central portion of a pile of blanks to normally support them, a 10 combined separating and supporting finger offset both laterally and lengthwise from said supporting and withdrawing members, means for deflecting an end of the outermost blank to permit entrance of the separating finger between it and the pile, and 15

means for reciprocating said supporting and separating members to alternately and oppositely withdraw them from and insert them beneath the pile of blanks.

16. A blank feeding mechanism comprising a suction device, a separating finger and blank removing members and a common reciprocating actuating member for all said parts, and means for confining the action of the suction device and of the blank removing device respectively to opposite movements of said actuating member. 20 25

In testimony whereof I affix my signature.

JOHN T. WILMORE.
